US00D390949S

United States Patent [19]

Fong et al.

[11] Patent Number: Des. 390,949

[45] Date of Patent: **Feb. 17, 1998

[54] **GRATE BAR KEY FOR STOKERS FEEDING
STEAM GENERATOR FURNACES**5,497,711 3/1996 Bobbitt 110/278
5,575,642 11/1996 Willis et al. ..... 110/291[75] Inventors: **Milton A. Fong, South Windsor; Mark
R. Hapgood, Tolland; Ivan Semyanko,
East Granby, all of Conn.**Primary Examiner—Antoine Duval Davis
Attorney, Agent, or Firm—Robert S. Smith, Esq.[73] Assignee: **Combustion Engineering, Inc.,
Windsor, Conn.**[57] **CLAIM**[**] Term: **14 Years**The ornamental design for a grate bar key for stokers feeding
steam generator furnaces, as shown and described.[21] Appl. No.: **64,352****DESCRIPTION**[22] Filed: **Dec. 30, 1996**

FIG. 1 is a plan view of one form of the invention;

[51] LOC (6) Cl. **23-03**

FIG. 2 is a bottom view of the embodiment of FIG. 1;

[52] U.S. Cl. **D23/396**

FIG. 3 is a left side view of the embodiment of FIG. 1;

[58] Field of Search **D23/396; 110/101 R.**

FIG. 4 is a front view of the embodiment of FIG. 1;

110/101 CF, 110, 165 R, 255, 257, 259,
281, 282, 288, 289, 283, 291; 126/110 R,
152 R, 182FIG. 5 is a right side view of the embodiment of FIG. 1; and,
FIG. 6 is a sectional view taken along the line 6—6 of FIG.
